UNITED STATES PATENT OFFICE.

LESLIE B. FISH, OF CHICAGO, ILLINOIS.

TRACTOR.

1,278,452.

Specification of Letters Patent. Patented Sept. 10, 1918.

Application filed June 18, 1917. Serial No. 175,314.

To all whom it may concern:

Be it known that I, LESLIE B. FISH, a citizen of the United States, residing at Chicago, in the county of Cook and State of Illinois, have invented certain new and useful Improvements in Tractors, of which the following is a specification.

My invention relates to tractors, and contemplates improvements in the construction and propulsion of such machines. One object is to construct a tractor the drive members of which shall constitute a large tractive area and shall be mounted so as to cause no strain on the machine irrespective of the character or contour of the ground or surface over which it passes. This object is attained by the employment of a plurality of drive members, some of which are mounted in an oscillatory or rocking frame, so that in passing over an elevation or into a depression the drive and steering members will properly engage the ground, that is, the action of these parts is not impaired, even though the ground be rough or undulating. Another object of my invention is the construction of a machine which shall have a maximum power with a minimum of parts, such parts being readily accessible. A further object of my invention is to obviate the use of gearing and substitute therefor chain and sprocket mechanism from the engine to the tractor wheels, and inclose such mechanism in housings. These housings, in addition to preventing the ingress of dirt, sand or foreign material, form receptacles for oil or any lubricant, so as to reduce friction to a minimum.

My invention will be better understood by reference to the accompanying drawings, in which,—

Figure 1 is a top view of a tractor embodying the features of my invention, some of the parts having been removed so as to clearly show the construction;

Fig. 2 is an enlarged end view of the machine;

Fig. 3 is an enlarged side view of the mechanism forming the subject matter of my invention; and

Fig. 4 is a top view of the parts shown in Fig. 3, some of the parts being shown in section so as to clearly reveal the construction.

The supporting frame 10 is constructed by the use of channel-shaped members 11, 12

and 13, and also intermediate members 14 and 15. To this frame are suitably secured downwardly extending members 16, 17 and 18, which support the main shaft 19, as clearly shown in Fig. 4. Pivotaly mounted upon this shaft is an auxiliary or rocking frame 20, preferably constructed of channel beams, and which has bearings 21 and 22 secured thereto, and through which the shaft 19 passes. The frame 20 also has secured at its front end, bearings 23 and 24, which are movable upon said frame, each of said bearings having elongated slots 25 and 26, respectively, through which pass bolts 27 and 28, respectively. Each of these bearings is provided with an upwardly extending lug 29, which is engaged by a screw 30 held by a lug 31 fastened to the frame 20. The bearings 23 and 24 support a shaft 32, which has secured thereon a sprocket 33 over which is trained a chain 34, which also is trained over a sprocket 35 secured to the shaft 19. Integral with the sprocket 35 is a similar sprocket 36, over which is trained a chain 37 which engages a sprocket 38 mounted upon a shaft 40 which is carried by bearings 41 and 42, which are mounted upon the frame 20. These bearings are adapted to be moved by means of the abutment screws 43, when desired, upon loosening nuts 43 which engage bolts 44 passing through elongated slots 45. These bolts are secured to the frame 20, and, as shown in Fig. 3, have sleeves 46 which act as spacing members between the flanges of the channel beams, the purpose being to secure a more rigid construction. The bearings 23, 24, 41 and 42 are movably mounted upon the frame 20, so as to tighten or loosen the chains 34 and 37 when desired. The shafts 32, 19 and 40 have secured thereto the traction wheels 47, 48 and 49, respectively, which, as shown in the drawings, are provided with lugs 50 for gripping the ground. The chains 34 and 37 and their associated sprockets are inclosed by means of a housing 51, which is preferably made in two parts so as to be easily assembled. These housings protect the chains and sprockets against unnecessary wear, and they also serve as containers for a lubricating medium, so as to reduce the wear on the parts to a minimum. As is shown particularly in Fig. 4, the shafts 32 and 40 pass through elongated slots 52 and 53, respectively, which are closed by plates 110

54 and 55, respectively, said plates being held in place by means of springs 56 and 57. These slots serve to permit the necessary movements of the shafts 32 and 40 with respect to the shaft 19 when necessary. As is shown in the drawings, the housing is supported mainly by the shaft 19, and any rocking movement of the frame 20 will of course rock the housing also. The shaft 19 has loosely mounted thereon a wheel 58 whose hub bears against the extension 18, and also a sleeve 59 secured to said shaft. The hub is provided with a clutch portion 60 adapted for operative engagement with a clutch member 61 upon actuation of the lever 62 pivoted at 63 to extensions 64 fastened to the member 15, the idea being that this wheel 58 in many instances may be run as an idler and at other times it is desirable to have it act as a traction or power wheel.

The tractor is preferably driven as follows:

The shaft 19 has secured thereto a sprocket 65 over which is trained a chain 66, which also engages a sprocket 67 secured to a jack shaft 68 which is rotatably mounted in bearings secured to the members 14 and 15. A large sprocket 69 is carried on this jack shaft, and a chain 70 which is trained over this sprocket is also trained over a sprocket 71 on the shaft 72 of the engine 73, which is suitably mounted upon the members 14 and 15. A suitable housing 74 incloses the chain 66 and its associated sprockets, and a similar housing 75 incloses the sprockets 69 and 71. These housings are adapted to contain a lubricating medium, and they also serve to prevent dirt and sand from gaining access to the operating parts. The frame 10 has fastened thereto a chain 76, which is also fastened to the frame 20 and serves to limit the oscillating or rocking movements of said frame when the wheels are passing over uneven or undulating surfaces.

The steering of the tractor is accomplished by means of a steering wheel 77 mounted in a fork 78 whose upper end is carried in a casting 79 secured to the frame 10. The fork terminates in a worm wheel 80 adapted to mesh with a worm 81 secured to a rod 82 terminating in a steering wheel 83 suitably supported by the frame.

It will be apparent from the foregoing description that my tractor embodies mechanism wherein the tractor members are adapted to adjust themselves to the contour of the ground or surface over which they pass, and these wheels are constructed so

that collectively they have an extremely 60 large area of engagement with the ground.

While I have herein described certain features and improvements constituting my invention, I do not wish to be limited to the precise arrangement shown, inasmuch as it will be apparent to those skilled in the art that changes and modifications may be made without departing from the spirit and scope of my invention.

I desire to secure the following claims: 70

1. In a tractor, the combination of a supporting frame, an engine, a main shaft, sprocket and chain mechanism disposed between said engine and main shaft, wheels mounted on said shaft, means for causing 75 one or both of said wheels to be driven as desired, an auxiliary frame rotatably carried by said main shaft, front and rear power wheels mounted in and surrounded by said auxiliary frame, and chain and sprocket means for driving said power wheels from said shaft. 80

2. In a tractor, the combination of a supporting frame, an engine, a main shaft, sprocket and chain mechanism disposed between said engine and main shaft, wheels mounted on said shaft, means for causing one or both of said wheels to be driven as desired, an oscillatory auxiliary frame carried by said main shaft, front and rear 85 power wheels mounted in and surrounded by said auxiliary frame, chain and sprocket means for driving said power wheels from said shaft, and inclosing frames for said chain and sprocket means. 90

3. In a tractor, the combination of a supporting frame, an engine, a main shaft, sprocket and chain mechanism disposed between said engine and main shaft, wheels mounted on said shaft, means for causing 100 one or both of said wheels to be driven as desired, an auxiliary rectangular frame rotatably carried by said shaft, front and rear power wheels mounted in said auxiliary frame, and chain and sprocket means for driving said power wheels from said shaft. 105

4. In a tractor, the combination of a frame, an engine, a main shaft, sprocket and chain mechanism disposed between said engine and main shaft, wheels mounted on said shaft, means for causing one or both of said wheels to be driven as desired, a rectangular rocking frame carried by said shaft, traction wheels mounted in and surrounded by said rocking frame, and chain and sprocket mechanism for driving said traction wheels from said shaft. 110

LESLIE B. FISH.
